(57) **CLAIM**

The ornamental design for a C-shaped neonate incubator, as shown and described.

DESCRIPTION

FIG. 1 is a front view of a C-shaped neonate incubator illustrating our new design;

FIG. 2 is a rear view thereof;

FIG. 3 is a left view thereof;

FIG. 4 is a right side view thereof;

FIG. 5 is a top view thereof;

FIG. 6 is a bottom view thereof; and,

FIG. 7 is a front perspective view thereof.

The portions of the device shown by broken lines form no part of the claimed design.
